CLAIM

The ornamental design for bottle for cosmetics, as shown and described.

DESCRIPTION

FIG. 1 is a perspective view of a bottle for cosmetics showing my new design;

FIG. 2 is a front view thereof;

FIG. 3 is a rear view thereof;

FIG. 4 is a plan view thereof;

FIG. 5 is a bottom view thereof;

FIG. 6 is a left side view thereof;

FIG. 7 is a right side view thereof; and,

FIG. 8 is a cross-sectional view thereof along the line 8-8 in FIG. 4.

The cap portion is transparent. The broken lines depict portions of the bottle for cosmetics that form no part of claimed design.

1 Claim, 3 Drawing Sheets
